H. L. E. PETERSON

RAZOR BLADE HOLDER

Filed June 3, 1921

Inventor:
Herman L. E. Peterson

By *Dr. J. Wilson*

Atty.

UNITED STATES PATENT OFFICE.

HERMAN L. E. PETERSON, OF ROCKFORD, ILLINOIS.

RAZOR-BLADE HOLDER.

Application filed June 3, 1921. Serial No. 474,666.

To all whom it may concern:

Be it known that I, HERMAN L. E. PETERSON, a citizen of the United States, residing at Rockford, in the county of Winnebago and State of Illinois, have invented certain new and useful Improvements in Razor-Blade Holders, of which the following is a specification.

This invention relates to holders for safety razor blades, and has more particular reference to that class adapted for holding straight-edge blades during honing and sharpening operations.

Many different forms of safety razor blade holders have been devised, but so far as I am aware none have been so constructed as to permit honing a blade after the fashion of and with the same hand motion as when honing an ordinary razor, and with the blade maintained at a predetermined angle with respect to the abrasive surface without causing undue filling of such surface as a result of the holder body contacting the surface throughout a substantial length. The primary object of the present invention, therefore, is to provide a razor blade holder which may be used either for honing on a flat stone or suitable abrasive surface in movements simulating the honing of an ordinary razor, and in which the holder has only a ball point contact with the stone, and through such contact determines the angle of the blade with respect to the stone.

In furtherance of this general object, I have provided a holder characterized by a handle equipped with blade-holding means and carrying beyond the outer end of the blade, a suitable roller or ball adapted to roll on a surface associated with the abrasive surface for determining the angle of a blade with respect thereto.

Another important object of my invention is to provide a razor blade holder of the character described, that is, including a roller or ball at the outer end of the blade, in which the blade is adapted to be automatically reversed through action of the roller member upon reversing the stroke.

A further object is to provide a holder of simple and novel design embodying such characteristics as to permit the holding of practically any straight-edge safety razor blade.

A still further object resides in the provision of a razor blade holder so designed that it will be practical and efficient for the purposes in mind and will consist of few parts so designed as to permit production at a comparatively low cost. 55

Other objects and attendant advantages 60 will be appreciated by those familiar with this art as the invention becomes better understood by reference to the following description when considered in connection with the accompanying drawings, in which— 65

Figure 1 is a side view of a razor blade holder embodying one form of my invention;

Fig. 2, a longitudinal sectional view 70 through the holder taken substantially on the line 2—2 of Fig. 1;

Fig. 3, a similar sectional view showing the blade-clamping means in the position with the blade removed;

Fig. 4, an end view of the handle; 75

Fig. 5, a side view partly in section of a razor blade holder embodying another form of my invention, showing it in a blade-holding position;

Fig. 6, a view looking at another side of the holder shown in Fig. 5, but with the blade-clamping members in a non-clamping position; 80

Fig. 7, a fragmentary view showing the blade holder in condition for stropping; 85

Fig. 8, a section taken on the line 8—8 of Fig. 7; and

Fig. 9, a view of the holder showing its use on a hone.

In one form of my invention shown in Figs. 1 to 4 inclusive, the blade may be honed and stropped after the fashion of an ordinary razor. In this form, the blade 12 is clamped between spring members 13 and 14, which in the present instance, are made from a single piece of material bent medially upon itself so that the ends 13 and 14 are in abutting relation. These clamping members carried by a handle 15, are so mounted thereon as to be capable of lengthwise movement with respect thereto for the purpose of clamping and releasing a blade. To this end, the members 13 and 14 are slidably lengthwise in a groove or socket 16 in the handle and pass through a bushing 17 carried by the 105 end collar 18 which is fixed to the handle.

As shown plainly in Fig. 2, the member 13 is considerably longer than the member 14, which has a laterally turned end 19 adapted to abut against the inner end of the bushing 17 for limiting outward movement of the clamping member. When the members are in their outermost position, the member 14 will spring open as shown in Fig. 6, permitting the insertion of a safety razor blade between the clamping members. The member 14 will then be pressed back against the member 13 and inserted in the bushing 17, whereupon the clamping members may be slid into the handle until limited by the wedging action of the members 13 and 14 against the inner walls of the bushing 17, resulting from separation of said members by the interposed blade. As a result of this construction, blades of different width, length and thickness may be clamped and securely held in the holder. It will be noted that in the present construction, the outer end portions of the members 13 and 14 are held against separation by a clip 21, and that the end portions 22 are bulged outwardly and bared or shaped to provide ball-retaining openings 23. A steel ball 24 of greater diameter than said holes 23 is interposed between the outer end portions 22 so as to be retained thereby and project through the openings 23. This ball, free to rotate in its retainer, is the only part of the holder which contacts the face of the stone or abrasive surface. It follows that when the holder is moved back and forth or in circular or any desired movement over the stone, the ball maintains the blade at a predetermined angle with respect to the stone by rolling thereon and there is practically no abrasive action between the holder proper and the stone. This will be obvious from the fact that the handle is held in one hand with the ball resting on the stone and the blade inclined with its cutting edge flat against the stone, similar to the position shown in Fig. 9. To remove the blade it is only necessary to pull the members 13-14 outwardly of the handle to a position limited by the stop 19, in which the part 14 is free to spring open, thereby releasing the blade.

In Figs. 5 to 9 inclusive, I have shown another embodiment of my invention in which the blade holder is adapted to be used for honing alone, or as in the former instance, either for honing or stropping. In this embodiment, the handle 25 carries a fixed shank 26 in the form of a rod, upon which is mounted for swinging movement about the axis of the rod, a blade holder comprising spring members 27 and 28. These members attached together at 29, are pivotally connected to the rod 26 through the agency of a band 31 and the slideable sleeve 32, each of which embraces the rod, the sleeve 32 also closely embracing the clamp-

ing members. By interposing a blade between said clamping members and sliding the sleeve 32 toward the blade, the latter will be clamped by and between the said members. It will now be observed that the blade holder is equipped at its outer end with a ball 33 which is seated between the part 31 and an expansion spring 34. In honing, the blade is positioned on a stone as shown in Fig. 9, and with the ball 33 resting on the stone the holder will be moved to the left. At the end of the stroke the movement will be reversed, thereby reversing rotation of the ball, which being urged against the blade holder by the spring 34, will instantly reverse the position of such holder, that is, cause the same to move by frictional contact with the ball to the position shown in dotted lines, Fig. 9, whereupon the ball will continue to roll as the spring pressure is not sufficient to overcome the frictional contact of the ball on the stone. Thus as the holder is moved back and forth the blade will be automatically reversed at the end of each stroke and by the same means which determines the working angle of the cutting edge. In the event that it is desired to use this form of holder for stropping or for honing in the manner first described above, the sleeve 35 which is slideable on the shank bracket 36 and is shaped to embrace the extended end 37 of the clamping member 28, will be moved forwardly on said shank bracket to the position shown in Fig. 7, to engage said end 37. In this manner the blade clamping members will be locked against rotation on the rod 26 and the blade will be held rigid with respect to the holder handle. In order to accommodate a blade having a thick rear edge 38, the clamping members may be cut away as at 39, to accommodate such edge. The clamping members may obviously be shaped to accommodate any blade; but as shown, they will hold practically all commercial blades. To remove a blade the sleeves 32 will be slid back to the dotted line position shown in Fig. 5, thus releasing the shorter clamping member 28, which will spring open as shown in Fig. 6, releasing the blade.

It is believed that the foregoing conveys a clear understanding of the objects prefaced above, and while I have shown several embodiments of the invention, it should be manifest that it is capable of considerable modification and change in design and construction without departing from the spirit and scope of the invention as expressed in the appended claim; in which—

I claim:

A razor blade holder of the character described comprising a handle, a blade holding means attached to the handle for holding a blade beyond one end thereof with an edge to be sharpened disposed parallel with and

laterally offset from the longitudinal axis of the handle, a ball, and a retainer for holding the ball in connection with said blade-holding means beyond the end thereof remote 5 from the handle and with the ball in alignment with said axis and projecting from opposed sides of the retainer on opposite sides of the blade, whereby the handle may be manipulated at will with either projecting side of the ball in contact with a sharpening 10 surface for determining the angle of the blade with respect to said surface during the sharpening or honing operation.

HERMAN L. E. PETERSON.
